United States Patent Office.

ASA T. SOULE, OF SAVANNAH, NEW YORK.

Letters Patent No. 80,095, dated July 21, 1868.

IMPROVEMENT IN HAY-RACK.

The Schedule referred to in these Letters Patent and making part of the same.

TO ALL WHOM IT MAY CONCERN:

Be it known that I, ASA T. SOULE, of Savannah, in the county of Wayne, and State of New York, have invented a new and useful Improvement in Hay-Racks; and I do hereby declare that the following is a full, clear, and exact description thereof, which will enable those skilled in the art to make and use the same, reference being had to the accompanying drawings, forming part of this specification, in which—

Figure 1 is a side view of my invention, and

Figure 2 is a cross-section of the same, taken in the line $y y$ in fig. 1.

Figure 3 shows a part of the device in use for other purposes.

Similar letters of reference indicate like parts.

This invention relates to certain new and useful improvements in hay-wagon racks, whereby a cheap, simple, and convenient construction is obtained.

I construct my hay-rack with straight beams or cross-pieces B B, and use them in connection with the ordinary wagon-box A. By using the rack in connection with the regular wagon-box, the rack is raised so high that the cross-pieces B can be made of straight pieces of wood, and no hoops, boxes, or similar devices are required to keep the load clear of the wagon-wheels, and no bed-frame for the rack is necessary, consequently making the construction very simple and cheap.

The rack is secured to the wagon-box by curved fingers e e, at the two forward beams B, and straight fingers or pins e', at the rear beam, all the fingers engaging with eye-bolts d, on the outside of the box. The method of securing the rack to the box is to first introduce the bent finger e into their eye-bolts, and then spring up the rear end of the rack, so that the pins e' can be dropped into the rear eye-bolts; and the rack is then locked fast in its position, as it can be removed only by bending the wooden stringer-pieces b, so that the pins e' are first disengaged, to allow the curved fingers e to be drawn out by a horizontal movement of the rack to the rear. The two forward pairs of eye-bolts d' are attached to the wagon-box in such manner as to be turned to lie horizontally, to aid in converting the wagon-box into a box for drawing grain, by attaching an extra rim, a, as shown in fig. 3. The ladder E is secured to the box by providing each of its legs e with a short pin or projection, f, (fig. 2), to engage with a corresponding hole or recess on the inside of the box. To attach the ladder to the box, its legs e e are compressed toward each other, until the pins f are brought opposite to the holes in the box, and the compressing force then being removed, the legs e e spring out and hold the pins f engaged with the holes in box A.

By this construction of frame, it is cheaper; for the reason that no bed-frame is required, the wagon-box answering that purpose, and the beams are made of straight pieces, and cost less than crooked ones or straight ones in conjunction with hoops or covers for the wheels. And the method of securing the parts together is also handy and cheap.

What I claim as new, and desire to secure by Letters Patent, is—

The crooked bolts e e and pins e', in connection with the eye-bolts d, box A, and rack B b, substantially as and for the purpose described.

The above specification of my invention signed by me, this 26th day of March, 1868.

ASA T. SOULE.
